GOVERNOR FOR LAWN MOWER ENGINES

Russell L. Morden, Lansing, Mich., assignor to Motor Wheel Corporation, Lansing, Mich., a corporation of Michigan

Application March 26, 1956, Serial No. 573,920

18 Claims. (Cl. 123—103)

This invention relates to a governor for the internal combustion engines such as used for propelling lawn mowers.

As with many internal combustion engines, the speed of the small engines used on power lawn mowers and similar implements is proportional to the amount of gas-air fuel mixture fed to the engine through an adjustable throttle valve which can be moved from a closed position to an open position, as desired, to meet demands for power. In the course of mowing a lawn variations in grass growth cause rapidly varying power demands on the mower engine. However, changing the engine speed to meet these demands by continual manipulation of a throttle valve control by the operator is not feasible.

The usual practice is to provide a throttle control means by which the engine speed can be adjusted to any desired level between predetermined minimum and maximum settings. In addition, a speed governor is provided which will automatically open the throttle when an applied load reduces engine speed below the desired level and close the throttle when release of the load allows engine speed to rise above the desired level.

In one type of governor, a vane in the form of a flat plate of metal is hinged at one edge and positioned adjacent the engine flywheel. The vane is operatively connected to the throttle. When the engine is operating, fins on the rotating flywheel direct air against the vane. If for any reason engine speed increases above the level set by the manual control, the resulting increased air pressure on the vane causes the vane to exert a force on the throttle in a closing direction.

To steady movement of the vane, and to insure reopening of the throttle valve to meet a demand for more power, means are provided for applying a force to the throttle valve opposite to the force applied by the vane. When the engine is operating these two forces tend to balance each other, holding the engine speed fairly constant at the desired level.

One such means commonly employed is a light cylindrical coiled tension spring connected at its ends between the throttle control means and the throttle valve. This type of spring has been found to have serious drawbacks for this application. First, a spring of the proper strength is fragile and readily subject to damage in assembly or in use. Second, the spring vibrates freely between its ends when the engine is running so that the spring is continually changing in overall length and thus exerts a variable force on the throttle valve. Third, such a spring tends to "overcorrect" by alternately stretching and contracting beyond the point of balance so that the engine speed continually fluctuates and does not reach a constant level. This fluctuation of engine speed is known as "hunting."

It is therefore an object of this invention to provide an improved vane type engine speed governor for an internal combustion engine.

It is a further object to provide such a governor that is not adversely affected by engine vibration.

2

It is a further object to provide a governor that will not "overcorrect" engine speed.

It is a further object to provide a governor which permits an engine of a given size to provide more available horsepower than when the same engine is used with a governor employing a cylindrical coiled tension spring.

It is a further object to provide a novel governor spring for use with a vane type speed governor on an internal combustion engine.

It is a further object of the invention to provide a governor spring possessing load-deflection characteristics that vary with time.

In the drawings:

Fig. 1 is a perspective view of a lawn mower including an engine embodying the invention.

Fig. 2 is a fragmentary part sectional plan view of the engine.

Fig. 3 is a perspective view of the improved governor, the engine being shown in dotted lines.

Fig. 4 is a sectional view taken along the line 4—4 in Fig. 2.

Fig. 5 is a view similar to Fig. 4 showing the parts in a different position.

Fig. 6 is a perspective view of the governor spring.

Fig. 7 is a sectional view taken along the line 7—7 in Fig. 2.

Referring to Fig. 1, a rotary type lawn mower may comprise a housing 10 on which wheels 11 are rotatably mounted for moving the housing along the ground. A handle 12 is pivoted to brackets 13 on the housing 10 for guiding the movement of the lawn mower along the ground. An engine 14 is mounted on the housing and is operatively connected to a rotary blade 15 which rotates about a vertical axis and cuts the grass as the mower is moved along the ground.

As shown in Fig. 2, the engine 14 comprises a cylinder block 16 and a flywheel 17 operatively connected to the crankshaft (not shown). The flywheel is provided with fins 18 which direct air across the block 16 to cool the block. The engine also includes a gas tank 20 and a housing 19 surrounding the cylinder block. A carburetor 21 is mounted on manifold 22 which is, in turn, mounted on the engine. An air cleaner 23 is supported on the carburetor for filtering the air which is supplied to the carburetor and the carburetor is connected to the gas tank 20 by a fuel line (not shown).

Referring to Fig. 3, the carburetor 21 includes a throttle valve 24 in the form of a butterfly or gate valve which controls the flow of gas-air mixture from the conduit 25 of carburetor 21 through manifold 22 to the engine. When the throttle valve is in position with the plane thereof extending longitudinally of conduit 25, the flow of gas-air mixture is substantially undisturbed. As throttle valve 24 is rotated bringing the plane thereof into a position transversely of conduit 25, the flow of gas-air mixture is progressively restricted and decreased. Valve 24 is mounted on the vertical shaft 26 rotatably mounted in the carburetor and having the upper end thereof projecting through the top of the body of the carburetor. A sector plate 27 is mounted on the upper end of shaft 26 with the plane thereof extending generally horizontally. The sector plate is provided with a multiplicity of holes 28 radially spaced from shaft 26.

As shown in Figs. 2 and 3, a governor vane 29, in the form of a flat piece of metal, is pivoted for rotation about a horizontal axis by means of a bracket 30 fastened to the cylinder block. A pin 31 hinges the vane 29 to bracket 30. A wire link 32 has one end thereof fastened to vane 29 and the other end thereof passing through one of the openings 28 in sector plate 27.

When the engine is running, the fins 18 on flywheel 17 force air against the vane 29 causing it to pivot about the

horizontal axis of pin 31 and exert a force on the throttle valve 24 through the link 32 tending to close conduit 25, to a position such as shown in Fig. 2.

The movement of throttle valve 24 in a closing direction is opposed by a governor spring 33 which has one end 34 thereof connected to one of the openings 28 in the sector plate 27 by a short wire link 35. As shown in Fig. 6, the governor spring 33 in the un tensioned condition comprises a straight upper end 34, a central looped portion 36 and a straight lower end 37. The coiled central portion 36 consists of a plurality of loops or coils in adjacent relationship. Governor spring 33 is loosely supported on a collar 38 mounted on manifold 22. A spring guide 39 is pivoted on the collar and comprises a pair of spaced ears 40 on either side of the spring 33 connected to each other by an elongated central portion 41 which acts as a stop against which the lower end 37 of the governor spring 33 bears.

As shown in Fig. 7, collar 38 includes a flange 42 adjacent and spaced from the outer end thereof. A throttle lever 43 in the form of a plate is mounted on the outer end of the collar and the collar is supported on the manifold by a bolt 44 extending through the collar. The lever 43 is mounted for pivotal movement with respect to collar 38 by means of a washer 45 positioned between the end of collar 38 and bolt 44. The space between the washer 45 and flange 42 of collar 38 is greater than the thickness of the lever 43. A throttle control cable 46 has one end thereof fastened to handle 12 (Fig. 1) and the other end thereof is positioned near the engine.

As shown in Fig. 3, the sheath 47 of control cable 46 is mounted on the engine by a bracket 48 and control wire 49 of cable 46 extends through sheath 47 and is connected to the lower end of throttle lever 43 at a point radially spaced from the collar 38. Throttle lever 43 is provided with an inwardly turned flange 50 through which a bolt 51 is threaded with the end thereof bearing against central portion 41 of the governor spring guide 39. A lock nut 52 is provided to adjust the relative position of lever 43 with respect to spring guide 39. When the engine is operated, the position of throttle lever 43 and governor spring guide 39 are fixed by the position of wire 49 of throttle control cable 46 thereby providing a stop for lower end 37 of the governor spring.

A shield 53 may be provided above the carburetor to protect the various parts and is connected to the housing by bolts 54 and to the manifold by a bracket 55 (Fig. 2).

The maximum throttle setting of the engine may be adjusted by operating the engine and pushing the throttle lever 43 toward the manifold until it strikes a stop 56 on the manifold (Fig. 4). With a tachometer on the engine shaft, the speed is adjusted to the desired level by turning bolt 51 thereby adjusting the position of the spring guide 39 and, in turn, the lower end 37 of governor spring 33. By screwing the bolt inwardly, the tension on governor spring 33 is increased, causing the throttle to open. When the desired setting is obtained, the bolt 51 is locked in position by tightening the lock nut 52. This adjustment may be made before the engine is mounted on the lawn mower and will not be affected by the mounting operation. The maximum setting of the throttle is thereby fixed and constant once it is adjusted.

When cable wire 49 is pulled from the remote position on the handle, lever 43 is moved away from the stop 56 on the manifold, permitting governor spring guide 39 to move with the lever by the action of the governor spring 33 to a new position. In this position the action of governor spring 33 in opposition to vane 29 is less; and, as a result, vane 29 will move or tend to move throttle valve 24 to a position more nearly near the closed position of the valve, thus, lowering the operating speed of the engine. Thus, by moving the cable, the operating speed of the engine is controlled but can never exceed the speed to which it has been set or adjusted, since the maximum

speed is positively determined by the contact of throttle lever 43 with stop 56 on the manifold.

The operation may be summarized as follows. Before the lawn mower is moved into grass, the engine is rotating at the maximum speed for the particular throttle cable setting and the rotation of the flywheel causes air to be forced against the vane 29. The air forced against the vane tends to cause vane 29 to pivot about its hinge and through wire link 32 exert a force on the sector plate 27 which thereby tends to move throttle 24 in a closing direction (Figs. 2, 4).

When the mower is moved through grass, the increased load causes the engine speed to drop, reducing the air pressure against vane 29. Governor spring 33, which tends to oppose the movement of the vane, then overcomes the force exerted on the vane and gradually moves throttle 24 in an opening direction until the force on the vane and the force exerted by the governor spring are again in balance (Figs. 3, 5).

As the mower is moved along the ground and encounters areas of grass which are not heavy, the load on the engine is decreased permitting the engine speed to increase and causing the pressure on vane 29 to increase thereby exerting a force on throttle 24 in a closing direction. As the lawn mower is moved into areas of grass which are heavier, the load on the engine is increased and the speed of the engine is decreased, thus reducing the air pressure on the vane and permitting governor spring 33 to move valve 24 in an opening direction to provide the necessary power.

The construction and arrangement of the governor spring is such that it is not adversely affected by the engine vibration.

Although I do not wish to be bound by the theory involved, I believe that the significant results obtained by the use of this governor are caused by the following action. The amount of deflection of the torsion type governor spring for the initial interval of time is from the free end and is not the full amount of deflection due to friction between the coils of the spring and the collar 38. However, engine vibration soon overcomes this friction, and the entire spring, including the coils, comes into operation. This action results in a slight time delay in opening the throttle, and this slight time delay allows the system to come into balance without overcorrection which produces "hunting."

As the load on the engine increases and the engine speed drops, the force on the vane due to air pressure decreases and the unsupported end of the governor spring moves the throttle in an opening direction. Engine vibration then allows the spring to move on collar 38, and the entire length of the spring comes into operation moving the throttle further in an opening direction. The final throttle position is such that the engine speed is very nearly that which it was before the load was increased. However, since the throttle action did not take place instantaneously, no overcorrection is made, and there is no tendency for the engine to "hunt."

It is believed that the friction between the coils of the governor spring and collar 38 produces a change of sensitivity with time. This permits the use of a flexible spring so that the governor can be quite sensitive. The increased sensitivity results in less loss of speed due to load change, and, as a result, the engine tends to run at a more constant speed. Also, by permitting the throttle to open completely with only a slight decrease in speed of the engine, a greater portion of the capacity of the engine may be utilized.

It can thus be seen that I have provided a more sensitive governor which will operate without "hunting" and which permits an engine of a given size to develop more horsepower for a given job.

I claim:

1. In a governor for an internal combustion engine,

having a throttle valve, and a fan operating in accordance with the speed of engine rotation, a vane mounted for pivotal movement in the path of air circulated by said fan, said vane being operatively connected to said throttle valve whereby when the vane responds to air flow from said fan the said throttle valve is moved in a closing direction, a post, and a torsion spring operatively connected to said throttle valve and opposing the closing action of said vane, said spring having a central portion comprising a plurality of coils wound around said post, one end of said spring being operatively connected to said throttle valve and the other end of said spring being anchored.

2. The combination set forth in claim 1 including means for adjusting the position of said anchored end of said spring.

3. In a governor for an internal combustion engine having a throttle valve, and a fan operating in accordance with the speed of engine rotation, a vane mounted for pivotal movement in the path of air circulated by said fan, said vane being operatively connected to said throttle valve whereby when the vane responds to air flow from said fan the said throttle valve is moved in a closing direction, a post, and a torsion spring operatively connected to said throttle valve and opposing the closing action of said vane, said spring having a central portion comprising a plurality of coils wound around said post, a sector plate connected to said throttle valve, and a link extending between said sector plate and one end of said spring, the other end of said spring being anchored.

4. In a governor for an internal combustion engine having a throttle valve, and a fan operating in accordance with the speed of engine rotation, a vane mounted for pivotal movement in the path of air circulated by said fan, said vane being operatively connected to said throttle valve whereby when the vane responds to air flow from said fan the said throttle valve is moved in a closing direction, a collar, a torsion spring operatively connected to said throttle valve and opposing the closing action of said vane, said spring having a central portion comprising a plurality of coils wound around said collar, the ends of said spring extending radially of said central portion and diverging, one end thereof being operatively connected to said valve, and a stop member contacting the other end of said spring.

5. The combination set forth in claim 4 including means for adjusting said stop member against which the other end of said spring rests.

6. The combination set forth in claim 5 including manually operated means connected to said adjustable stop member and extending to a position remote of said engine whereby the position of said stop member may be adjusted.

7. The combination set forth in claim 5 wherein said stop member comprises a pair of spaced ears rotatably mounted on said collar and a central portion connecting said ears, said central portion extending radially and outwardly away from said collar, the end of said spring extending along said central portion.

8. The combination set forth in claim 7 wherein said means for adjusting said stop member comprises a lever mounted for rotation about the axis of said collar, a bolt threaded through said lever in such a position that the end of said bolt contacts the central portion of said stop member.

9. In a governor for an internal combustion engine having an intake passageway for supplying a combustible gaseous mixture to said engine and a throttle valve positioned in said passageway for controlling the flow of combustible mixture to said engine, said valve being mounted for rotation about an axis transverse of said passageway, said engine including a crankshaft and a fan operatively connected to said crankshaft and operating in accordance with the speed of the engine, a vane

mounted for pivotal movement in the flow of air from said fan, means connecting said vane to said throttle valve in such a manner that when the vane responds to air flow from the fan the throttle valve is moved in a closing direction, a torsion spring operatively connected to said throttle valve, opposing the closing action of said vane and biasing the throttle valve to open position, said spring including a central portion having a plurality of coils, the ends of said spring extending radially outwardly from said central portion and diverging with respect to each other, one end of said spring being operatively connected to said throttle valve, and a stop member for engaging the other end of said spring and limiting its movement in one direction, said spring being mounted for pivotal movement about the axis of said central coiled portion.

10. In a governor for an internal combustion engine having a carburetor, said carburetor having a conduit communicating with said engine, a throttle valve positioned in said conduit and controlling the flow of combustible mixture to said engine, said throttle valve being mounted on a shaft extending transversely of said conduit, one end of said shaft projecting through the body of said carburetor, a sector plate mounted on the end of said shaft and having a multiplicity of holes therein radially spaced from the axis of said shaft, said engine including a crankshaft and a flywheel operatively connected to said crankshaft, said flywheel being so constructed and arranged that upon rotation thereof air is circulated about said engine for cooling said engine, a vane pivotally mounted on said engine in the path of air circulated by said flywheel and adapted to be moved by the air pressure caused by rotation of said flywheel, a link extending between said vane and one of said holes in the sector plate in such a manner that when the engine is operated air pressure on the vane tends to move the vane causing the sector plate to rotate and move the throttle valve in a closing direction, a torsion spring operatively connected to said sector plate and opposing the action of said vane in tending to move said throttle valve in a closing direction, a collar, said spring having a central portion comprising a plurality of coils wound around said collar, said spring being rotatable with respect to said collar, the ends of said spring extending radially of said central portion and diverging with respect to each other, a link connecting one end of said spring to one of the holes in said sector plate, and a stop member opposing the movement of the other end of said spring in one direction.

11. The combination set forth in claim 10 wherein said stop member comprises a member mounted for rotation about the axis of said collar and having a portion thereof spaced radially from the axis of said collar, the end of said spring contacting said radially spaced portion, a lever mounted for rotation with respect to the axis of said collar, a bolt threaded into said lever and having the end thereof contacting said radially spaced portion of said member, and means fixing the position of said lever.

12. The combination set forth in claim 11 wherein said means fixing the position of said lever comprises a cable having one end thereof connected to said lever, the other end of said cable extending to a position remote of said engine whereby by moving said cable the position of said lever may be adjusted thereby adjusting the position of said stop member and, in turn, the position of the end of said spring.

13. In a governor for an internal combustion engine having a throttle valve and a governor element movable in opposite directions in response to variations in the speed of the engine, a torsion spring comprising a central coiled portion with the ends of said spring extending outwardly from said central portion, said spring being mounted for pivotal movement about the axis of said central coiled portion, one end of said spring being operatively connected to said governor element, and a

stop member for engaging the other end of said spring and limiting its movement in one direction.

14. In a governor for an internal combustion engine having a throttle valve and a fan operating in accordance with the speed of engine rotation, a vane mounted for pivotal movement in the path of air circulated by said fan, said vane being operatively connected to said throttle valve whereby when the vane responds to increased air flow from said fan the throttle valve is moved in a closing direction, a torsion spring comprising a central coiled portion with the ends of said spring extending outwardly from said central coiled portion, said spring being mounted for pivotal movement about the axis of said central coiled portion, one end of said spring being operatively connected to said throttle valve, and a stop member for engaging the other end of said spring and limiting its movement in one direction.

15. The combination set forth in claim 14 including a post supporting said central portion of said spring.

16. In a governor for an internal combustion engine having an intake passageway for supplying a combustible gaseous mixture to said engine and a throttle valve positioned in said passageway for controlling the flow of combustible mixture to said engine, said valve being mounted for rotation about an axis transverse of said passageway, said engine including a crankshaft and a fan operatively connected to said crankshaft and operating in accordance with the speed of the engine, a vane mounted for pivotal movement in the path of air circulated by said fan, means connecting said vane to said throttle valve in such a manner that when the vane responds to increased air flow from the fan the throttle valve is moved in a closing direction, a torsion spring comprising a central coiled portion with the ends of said spring extending outwardly from said central coiled portion, said spring being mounted for pivotal movement about the axis of said central coiled portion, one end of said spring being operatively connected to said throttle valve, and a stop member for engaging the other end of said spring and limiting its movement in one direction.

17. In a governor for an internal combustion engine having a throttle valve, and a fan operating in accordance with the speed of engine rotation, a vane mounted

for pivotal movement in the path of air circulated by said fan, said vane being operatively connected to said throttle valve whereby when the vane responds to increased air flow from said fan the throttle valve is moved in a closing direction, a torsion spring comprising a central coiled portion with the ends of said spring extending outwardly from said central coiled portion, said spring being mounted for pivotal movement about the axis of said central coiled portion, one end of said spring being operatively connected to said throttle valve, a movable stop member for engaging the other end of said spring and limiting its movement in one direction, and manually operated means connected to said movable stop member and extending to a position remote of said engine whereby the operating speed of the engine may be varied during operation by moving said stop member.

18. In a governor for an internal combustion engine having a throttle valve, and a fan operating in accordance with the speed of engine rotation, a vane mounted for pivotal movement in the path of air circulated by said fan, said vane being operatively connected to said throttle valve whereby when the vane responds to increased air flow from said fan the throttle valve is moved in a closing direction, a torsion spring comprising a central coiled portion with the ends of said spring extending outwardly from said central coiled portion, a lever pivotally mounted on said engine, means for mounting said spring for pivotal movement about the axis of the lever, said central coiled portion of said spring being axially aligned with the axis of said lever, one end of said spring being operatively connected to said throttle valve, the other end of said spring engaging said lever and limiting its movement in one direction, and means operatively connected to said lever for adjusting the position of said stop during the operation of the engine to vary the engine speed.
